DESIGN FOR A COMBINED ORNAMENTAL DISPLAY AND NAME PLATE

Bernard M. Solomon, Montgomery, Ala.

Application May 23, 1936, Serial No. 62,797

Term of patent 7 years

To all whom it may concern:

Be it known that I, Bernard M. Solomon, a citizen of the United States, residing at Montgomery, in the county of Montgomery and State of Alabama, have invented a new, original, and ornamental Design for a Combined Ornamental Display and Name Plate, of which the following is a specification, reference being had to the accompanying drawing, forming part thereof.

The figure is a plan view of a combined ornamental display and name plate, showing my new design. The plate is substantially thin and flat.

I claim:

The ornamental design for a combined ornamental display and name plate, substantially as shown and described.

BERNARD M. SOLOMON.
